UNITED STATES PATENT OFFICE.

GEORGE ANTHONY SINGERLY, OF PHILADELPHIA, PENNSYLVANIA.

DESIGN FOR A HORSESHOE.

SPECIFICATION forming part of Design No. 27,042, dated May 11, 1897.

Application filed April 1, 1897. Serial No. 630,309. Term of patent 14 years.

To all whom it may concern:

Be it known that I, GEORGE ANTHONY SINGERLY, a citizen of the United States, residing in the city and county of Philadelphia, State of Pennsylvania, have invented and produced a new and original Design for a Horseshoe, of which the following is a specification, reference being had to the accompanying drawings, forming a part thereof.

10 The leading feature of my design for a horse or animal shoe is a shoe having on the tread depending rims extending around the toe portions thereof and depending segmental ribs at the heel portions thereof.

15 Figure 1 represents a bottom plan view of a horseshoe embodying my design. Fig. 2 represents a section of the shoe on line x x ,

Fig. 1, and an elevation of the inner side thereof. Fig. 3 represents a rear end view of one of the heel portions of the shoe. 20

In the drawings, A designates a shoe having on the tread thereof the depending rims B B, which extend around the toe portions of the shoe.

C designates segmental ribs which depend from the heel portions of the shoe. 25

What I claim is—

The design for a horseshoe substantially as described and shown.

GEORGE ANTHONY SINGERLY.
